UNITED STATES PATENT OFFICE.

EDWARD B. HESS, OF NEW YORK, AND LEWIS C. MYERS, OF FREEPORT, NEW YORK, ASSIGNORS TO ROYAL TYPEWRITER COMPANY, INC., OF NEW YORK, N. Y., A CORPORATION OF NEW YORK.

RIBBON-FEEDING MECHANISM FOR TYPEWRITING MACHINES.

Application filed April 30, 1925. Serial No. 26,878.

To all whom it may concern:

Be it known that we, EDWARD B. HESS, a citizen of the United States, and resident of the city, county, and State of New York, and LEWIS C. MYERS, a citizen of the United States, and resident of Freeport, in the county of Nassau and State of New York, have invented certain new and useful Improvements in Ribbon-Feeding Mechanism for Typewriting Machines, of which the following is a specification.

This invention relates to devices for feeding the ribbon step by step upon the actuation of a type key. An object of the invention is to provide such devices which shall be simple and efficient in construction and will lend themselves particularly to use in a small compact machine. The invention is illustrated in connection with a portable Royal typewriter but is not necessarily limited in its application thereto.

A further object of the invention is the provision of means carried by the type segment for supporting the ribbon spool shaft, the ribbon driving shaft, the automatic reverse mechanism and other features of the ribbon mechanism. Further objects of the invention will be apparent from the following detailed description and the appended claims.

30 In the drawings:

Figure 1 is a vertical transverse section of the machine taken in front of the ribbon spools with parts in elevation.

Figure 2 is a top plan view.

35 Figure 3 is a plan view taken substantially on the line 3—3 of Figure 4.

Figure 4 is a section taken on the line 4—4 of Figure 3.

40 The typewriting machine as illustrated includes a frame A, type bar segment B, type guide C, ribbon vibrator D and the other usual instrumentalities of a typewriting machine. So far as our invention is concerned, these parts may be of any desired character.

45 Ribbon spools E are enclosed in cups F and mounted on shafts 1 which are supported in offset arms 2 and 3 of a bracket 4 which is attached to the type bar segment B. Fastened to the lower end of each shaft 1 is a

50 bevel gear 5 with one of which gears meshes a bevelled gear 6 at the right hand end of the machine and with the other of which meshes a similar bevelled gear 7 at the other side of the machine; this gear facing in opposite di-

rection to the gear 6. The gears 6 and 7 are fast on a driving shaft 8 which is mounted for longitudinal movement as well as rotation in the downturned arms 9 bent from the arms 3 of the brackets 4. Near the right hand side of the machine the shaft 8 has fast thereon a large ratchet wheel 10 with fine teeth which are engaged by a pawl 11. This pawl is pivotally connected at 12 to an arm 13 extending upward from one of the side arms 14 of the universal bar frame 15 which comprises a shaft 15 and a cross connecting rod 16. Each type key lever has a rearward end 17 which underlies the rod 16. It is therefore apparent that on each depression of a printing key the upward motion imparted to the rod 16 will rock the universal frame and move the pawl 11 forward, giving a step movement to the ratchet wheel 10 and thereby turning one or the other of the gears 5 and the ribbon spool 75 shaft to which it is fastened. Each key lever is fulcrumed on a shaft 19 and extends through a guide comb 20. This comb also guides the pawl 11 in its reciprocating movements and a spring 21 attached at one end to said pawl and at its other end to an ear on the guide comb holds the pawl in engagement with the ratchet wheel 10. The holding pawl 22 also engages the ratchet wheel 80 and this pawl is mounted on the pivot rod 19 and is also guided by the comb 20.

Near the right hand side of the machine the shaft 8 is provided with a collar 23 which has two grooves therein separated by a sharp pointed ridge. In these grooves engages the nose 24 of a pawl member pivoted at 25 on an ear 26 offset from the arm 9 of the bracket 4. To an upwardly extending arm 28 of the pawl is attached one end of a spring 27, the other end of which is attached to an ear on the member 26. This spring tends normally to hold the pawl 24 in one or the other of the grooves of the collar 23 and thus retain the shaft 8 in one or the other of its longitudinal positions.

100 There is also illustrated herein and will be briefly described, a ribbon reversing mechanism which, however, is not claimed in this application as it is described and claimed in the application of George F. Handley, Serial No. 746,577, filed October 29th, 1924. This mechanism comprises a forked ribbon guide through which passes the ribbon and

which is engaged after the ribbon is nearly unwound from the spool, by a projection 30 on the ribbon. This ribbon guide is longitudinally slidable on a bracket member 31 offset from the bracket 4 and is connected at 32 to the upwardly extending arm 33 of a bell crank lever 34 pivoted at 35 to a projecting ear of the bracket 4. The short arm 37 of this bell crank lever has a pin 38 which works in a slot 39 in the upper end of a 10 slidable member 40 and the arm 38 is connected to the member 40 by a coiled spring 41. This member 40 is guided in the lower portion 42 of the frame and has a pawl 43 15 adapted to be brought into engagement with a multiple toothed worm member 44 on the shaft 8.

It is obvious that when the sliding member 29 is moved by engagement of the projection 30 of the ribbon therewith, the bell crank lever 34 will be rocked, lifting the 20 sliding member 40 by the spring 41. As the pawl 43 is brought into engagement with the multiple toothed worm 44, continuing 25 rotation of the shaft will cause an endwise movement thereof and as soon as the pawl 24 rides up out of one groove in the member 23, it will snap over suddenly into the other 30 groove, affording a sudden endwise movement of the shaft 8 from the position shown in Figure 1 to a position in which the gears 5 and 7 will be in mesh while the gears 5 35 and 6 will be unmeshed. Subsequent rotation of the shaft 8 will therefore afford a feeding movement of the ribbon in the opposite direction. The shaft 8 is provided at its outer ends with finger pieces 45 by which the shaft may be manually rotated to feed the ribbon from one spool to the other or 40 may be manually moved endwise for the purpose of reversing the ribbon feed at any desired time.

It is believed that the operation of the mechanism constituting this invention will 45 be clear from the above description. It is to be noted that the drawings show certain portions of the typewriting machine which are not described and claimed as they have no particular relation to the invention. 50 They are merely illustrated to show the relation of the ribbon mechanism to the other portions of the machine and the compact arrangement of the parts. It is obvious that various detail changes may be made in the 55 precise embodiment of the invention without in any way departing from the spirit thereof. The invention is therefore to be regarded as limited only by the scope of the appended claims.

60 We claim as our invention:

1. Ribbon feeding mechanism for typewriting machines having a guide comb for the key levers, said mechanism comprising a 65 driving shaft, a ratchet wheel thereon, a universal bar frame having an upstanding

arm and actuated by the rear ends of the key levers, a pawl pivoted to said arm and engaging the ratchet wheel near the top thereof, and a guide slot in said comb for the pawl.

2. Ribbon feeding mechanism for typewriting machines having a guide comb and pivot shaft for the key levers, said mechanism comprising a driving shaft, a ratchet wheel thereon, a universal bar frame having an upstanding arm and actuated by the rear ends of the key levers, a pawl pivoted to said arm and engaging the ratchet wheel near the top thereof, a guide slot in the comb for the pawl and a holding pawl 75 mounted on the pivot shaft.

3. Ribbon feeding mechanism for typewriting machines comprising a driving shaft, a ratchet wheel thereon, a substantially horizontal universal bar frame having a rear transverse bar and an upright arm, a pawl pivoted to the upper end of said arm and engaging the ratchet wheel near the top thereof, guiding means for said pawl, and a holding pawl also positioned 80 by said guiding means.

4. Ribbon mechanism for typewriting machines comprising a pair of brackets supported by the type segment, and ribbon spool shafts, driving shaft and reversing mechanism all carried by the brackets.

5. Ribbon mechanism for typewriting machines comprising a pair of brackets supported by the type segment, and ribbon spool shafts, a longitudinally moveable driving shaft, means for holding it in adjusted position, and reversing mechanism all carried by the brackets.

6. Ribbon mechanism for typewriting machines comprising a pair of brackets supported by the type segment, a longitudinally moveable driving shaft supported by said brackets, means for holding said shaft in either of its longitudinal positions, said means also carried by one of said brackets, and means on each end of the shaft for rotating the same or giving it endwise movement.

7. In a typewriting machine the combination of key levers, ribbon driving mechanism comprising a ratchet wheel and a driving pawl therefor, and a single comb acting as a guide for said key levers and driving pawl.

8. In a typewriting machine the combination of key levers, ribbon driving mechanism comprising a ratchet wheel, a driving pawl and a holding pawl, and a single comb acting as a guide for said key levers, driving pawl, and holding pawl.

In testimony whereof, we have hereunto subscribed our names.

EDWARD B. HESS.
LEWIS C. MYERS.
